UNITED STATES PATENT OFFICE.

ARNOLD E. HOUGE, OF BADGER, IOWA.

STRAINING DEVICE FOR EAVES-SPOUTINGS.

1,231,356.

Specification of Letters Patent. Patented June 26, 1917.

Application filed April 23, 1917. Serial No. 165,199.

To all whom it may concern:

Be it known that I, ARNOLD E. HOUGE, a citizen of the United States, residing at Badger, in the county of Webster and State 5 of Iowa, have invented new and useful Improvements in Straining Devices for Eaves-Spoutings, of which the following is a specification.

This invention relates to certain new and 10 useful improvements in straining devices for eaves spouting, and the primary object of the invention is to produce a strainer of finely woven fabric and a holding device of a novel construction for such fabric, the 15 fabric, of course, being designed for catching and retaining dirt and like substances passing through the spout.

With the above and other objects in view 20 the improvement resides in the construction, combination and arrangement of parts set forth in the following specification and falling within the scope of the appended claims.

In the drawing:

Figure 1 is a perspective view illustrating 25 the application of the improvement,

Fig. 2 is a central vertical longitudinal 30 sectional view through the same, and

Fig. 3 is a perspective view of a strainer holder, the ring members being separated as 35 when the fabric strainer is to be arranged therebetween.

The eaves or downspout 1 may be arranged above a cut-off in the spout or conductor and the spout is provided upon its 35 outer face with a slot or opening 2, the upper wall provided by the opening being preferably inclined, so that the space between the upper and lower walls of the said opening is greatest at the center of the 40 opening.

The holding device for the fabric strain 3 is broadly indicated by the numeral 4, and comprises two ring members 5 and 6 respectively. The lower ring member is 45 preferably formed of a continuous stretch of wire and has its ends offset, as at 7, and continued in an outward direction in parallelism providing the spaced arms 8. These arms at their outer ends are bent to provide

the handle portion 9, and the said arms, at 50 the juncture with the handle, are bent upon themselves or otherwise formed with up-standing ears 10 between which is arranged a pivot 11 that is designed to receive the arm 12 of the ring member 6. The ring 55 member 6 is of a size to be snugly received in the ring member 5 and in reality comprises a flat band, the outer edge of which being formed with a continuous flange 10 which is designed to rest upon the wire ring 60 member 5 when the rings are associated to arrange the fabric filtering medium therebetween. The device is inserted through the opening in the conducting pipe or spout as illustrated in Figs. 1 and 2 of the drawings 65 and the fabric filtering cloth will contact with the inner periphery or bore of the said pipe so that particles of dirt and the like passing through the pipe will be received upon the filtering member, while at the same 70 time the water will readily permeate through the said filtering member.

Having thus described the invention, what I claim is:

1. In combination with a down-spout or 75 the like, having an opening in one of the sides thereof, of a holder member including a handle and two pivoted rings designed to receive therebetween a strip of fabric providing a filtering member and which is 80 adapted to be inserted through the opening in the pipe, as and for the purpose set forth.

2. A holding means for fabric filters for 85 down-spouts or the like, comprising two ring members each formed with outstanding arms, one of the ring members being in the nature of a metallic band, the outer edge of which is flanged, the arm of the said member being pivotally secured to the arm of the first mentioned member whereby the 90 second mentioned ring will be swung to within the first mentioned ring with the flange of the first mentioned ring resting upon the upper edge of the second mentioned ring. 95

In testimony whereof I affix my signature.

ARNOLD E. HOUGE.
